INVENTOR,
William A. Day,
BY David E. Lain,
ATTORNEY.

Patented Dec. 14, 1926.

UNITED STATES PATENT OFFICE.

WILLIAM A. DAY, OF BELLINGHAM, WASHINGTON, ASSIGNOR OF ONE-HALF TO FRED S. WALKER, OF BELLINGHAM, WASHINGTON.

FILE-HANDLE CLAMP.

Application filed February 24, 1926. Serial No. 90,249.

My invention relates to improvements in file handle clamps, and one of the objects of my improvement is to provide a file handle clamp which is operated mechanically to strongly hold and easily release the files, and which is of simple design and not expensive construction. And a further object of my improvement is to provide a file handle clamp sufficiently adjustable to accommodate several sizes and kinds of files.

I attain these objects with the mechanism illustrated in the accompanying sheet of drawings in which Figure 1 is a plan view of my file clamp, Figure 2 is a side elevation of Fig. 1 showing the file handle, Fig. 3 is a segregated view of the wing head screw used in my clamp, Fig. 4 is a segregated rear elevation of the ferrule used in my clamp, and Fig. 5 is a segregated rear elevation of one of the jaws used in my clamp.

Similar characters refer to similar parts throughout.

More particularly: On file handle 6 is fixed ferrule 7. In the ferrule are two parallel grooves 8, 8 transversally of the same near its outer end. Also in the rear side only of the ferrule is hole 9 centrally placed between grooves 8, see Fig. 4. Mounted in the outer end of the ferrule are two semicylindrical jaws 10 and 14. Both jaws have central longitudinal V grooves 13 juxtaposed when in operative position. In each of said jaws are parallel side grooves 11, 11 registering with grooves 8, 8 in ferrule 7 when the former are mounted in operative position in said ferrule. Also in jaw 10 only is tapped hole 12, see Fig. 5, axially registering with hole 9 in ferrule 7 when said jaw is mounted in the ferrule. Jaws 10 and 14 are alike in every particular except jaw 10 has tapped hole 12 therein.

A slide frame consisting of similar legs 15, 15 joined by cross head 16 is mounted for transverse reciprocation in notches 8, 8 in ferrule 7 with legs 15 engaged in said notches. On legs 15 are also mounted jaws 10 and 14 for reciprocation with notches 11 engaged with said legs. Through registering holes in the ends of legs 15 is rivet 17 on which is mounted cam lever 18, 18 for oscillation. Cam 18 is eccentric on rivet 17 and bears on the body of ferrule 7 between legs 15. When handle 18 is in its full-line position the shortest contacting ra-

dius of said cam may bear on ferrule 7, while when said lever 18 is in its dotted position at 18' the longest contacting radius of the cam may bear on said ferrule body. In the latter case the slide frame is drawn from its full-line position to its dotted position at 15', 16'.

In a hole in cross head 16 axially registering with hole 9 in ferrule 7 is mounted wing head screw 19, 20 for revolution or reciprocation. Said screw is carried forward to engage with tapped hole 12 in jaw 10. On screw 19 is mounted coil spring 21 which is also loosely mounted in hole 9 in ferrule 7 and reacts between jaw 10 and cross head 16.

In practice: The file tang may be clamped between jaws 10 and 14 when in grooves 13 or the shank end of the file body may be clamped between the jaws as desired. Screw 19 may protrude through jaw 10, as illustrated, or it may be drawn back within the body of said jaw. In the former case the screw alone bears on that side of the file while in the latter case jaw 10 bears on said file. This possibility of clamping the file between jaw 14 and the end of screw 19 or between the two jaws as desired allows of using any given size of handle clamp with a greater variety of sizes of files than otherwise would be possible.

When setting screw 19 for any particular file then between the jaws preferably the adjustment of said screw provides that when handle 18 is turned to its position at 18' the coils of spring 21 will bear on each other as illustrated. Hence, when a file is clamped in this handle spring 21 serves as a block between jaw 10 and head 16. In all cases the adjustment of screw 19 preferably allows handle 18 to be carried to its position at 18' when the clamping is complete. During the period of adjusting the clamp to the file between the jaws the flexibility of spring 21 reacting between head 16 and jaw 10 aids in that the file may be lightly held in the clamp thereby during the time of setting the clamp to fit said file.

Having thus disclosed my invention, what I claim as new therein and desire to secure by Letters Patent is,—

1. In a file handle clamp in combination, a file handle ferrule having a pair of parallel, diametrically-disposed transverse grooves therein and a hole through its wall between

said grooves, a slide frame consisting of two parallel legs and a head joining them at one end mounted for reciprocation in said ferrule grooves, a handle cam mounted for oscillation on a pivot in the ends of said frame legs adapted to bear on said ferrule, two semicylindrical jaws having transverse grooves therein mounted within said ferrule on said frame legs for reciprocation thereon, and a spring mounted in said ferrule hole for reaction between said frame head and one of said jaws.

2. In a file handle clamp in combination, a file handle ferrule having a pair of parallel, diametrically-disposed transverse grooves therein and a hole through its walls between said grooves, a slide frame consisting of two parallel legs joined at one end by a cross-head having a central hole there-through mounted for reciprocation in said ferrule grooves, a handle cam mounted for oscillation on a pivot in the ends of said frame legs adapted to bear on said ferrule, two semicylindrical jaws having transverse grooves therein mounted within said ferrule on said frame legs for reciprocation one of said jaws having a radial tapped hole there-in between said grooves, a screw mounted in said hole in said crosshead and in said hole in said ferrule engaged in said tapped hole in said one jaw, and a sleeve mounted in said hole in said ferrule on said screw adapted to bear on said one jaw and on said frame crosshead.

in said ferrule in engagement with said 30 tapped hole in said one of said jaws, and a spring mounted in said hole in said ferrule and on said screw adapted to react between said one of said jaws and said frame cross-head.

3. In a file handle clamp in combination, a file handle ferrule having a pair of parallel, diametrically-disposed transverse grooves therein and a hole through its walls between said grooves, a slide frame consisting of 40 two parallel legs joined at one end by a crosshead having a central hole therethrough mounted for reciprocation in said ferrule grooves, a handle cam mounted for oscillation on a pivot in the ends of said frame 45 legs adapted to bear on said ferrule, two semicylindrical jaws having transverse grooves therein mounted within said ferrule on said frame legs for reciprocation one of said jaws having a radial tapped hole there-in between said grooves, a screw mounted in said hole in said crosshead and in said hole in said ferrule engaged in said tapped hole in said one jaw, and a sleeve mounted 50 in said hole in said ferrule on said screw 55 adapted to bear on said one jaw and on said frame crosshead.

WILLIAM A. DAY.
